CLAIM

The ornamental design for a digital video camera with a connector, as shown and described.

DESCRIPTION

FIG. 1 is a top, front and left side perspective view of a digital video camera with a connector showing our new design;

FIG. 2 is a top, rear and left side perspective view thereof;

FIG. 3 is a top, front and left side perspective view thereof, with the connector extended;

FIG. 4 is a top, rear and left side perspective view thereof, with the connector extended;

FIG. 5 is a right side elevational view thereof, with the connector extended;

FIG. 6 is a left side elevational view thereof, with the connector extended;

FIG. 7 is a top plan view thereof, with the connector extended;

FIG. 8 is a bottom plan view thereof;

FIG. 9 is a front elevational view thereof, with the connector extended; and,

FIG. 10 is a rear elevational view thereof, with the connector extended.
